CABINET FOR INSTRUMENTS OR THE LIKE

Robert Schlaich, Robert Bosch-Strasse 103,
Stuttgart, Germany

Filed Apr. 6, 1960, Ser. No. 60,064

Claims priority, application Germany Oct. 26, 1959

Term of patent 14 years

(Cl. D52—6)

FIG. 1

FIG. 2

FIG. 3

FIG. 4

FIG. 5

FIG. 1 is a front elevational view of a cabinet for instruments or the like, showing my new design;
FIG. 2 is a side view thereof;
FIG. 3 is a top plan view;
FIG. 4 is a bottom view thereof; and
FIG. 5 is a perspective view thereof.

The essential features of the design reside in the portions shown in full lines on the drawing.

I claim:

The ornamental design for a cabinet for instruments or the like, as shown and described.
